WIRE ROPE

Filed Feb. 7, 1931

UNITED STATES PATENT OFFICE

ROBERT CHARLES GEORGE JENKIN, OF BIRMINGHAM, ENGLAND, ASSIGNOR TO
WRIGHTS' ROPES LIMITED, OF BIRMINGHAM, ENGLAND, A COMPANY OF GREAT
BRITAIN

WIRE ROPE

Application filed February 7, 1931, Serial No. 514,225, and in Great Britain September 2, 1930.

This invention relates to wire ropes of the flattened strand type, in which the strands are of a more or less triangular form and are built up of one or more layers of wires 5 laid upon a central core of a substantially triangular shape. Heretofore the cores of such flattened strands have consisted of a single wire of triangular section, or of three round wires grouped in triangular formation. 10 In the former case, however, especially when the rope is subjected to excessive flexing under heavy compressional loads, the single triangular core wire tends to fracture at the edges or corners, owing to the considerable 15 radius from the axis of the wire at which the apices of the triangle are situated, and, moreover, the said triangular wire tends to cut and damage the adjacent covering wires. In the other case, where the core is composed 20 of three wires grouped in triangular formation, the said wires tend to open out or spread under compression, thereby deforming the shape of the strand. The object of the present invention is to provide an improved construction of core for a flattened strand, whereby the above disadvantages are 25 avoided.

According to the invention, the core consists of a single central wire having three 30 spaced longitudinal grooves, with wires located in the said grooves, the arrangement being such as to form a composite core of a triangular or substantially triangular form, with the wires in the grooves lying at the 35 corners of the triangle. The core thus formed may be given a spiral lay or twist and gives freedom of flexure to the rope without being liable to fracture under compression.

40 Figure 1 of the accompanying drawings shows a sectional view of several strands of a wire rope, in which the said strands are each provided with a composite core constructed in accordance with this invention.

45 Figure 2 is a sectional view of the core only of one of the strands.

Figure 3 represents an elevational view of one of the strands on a smaller scale and cut 50 away to expose portions of the central and

outer wires of the core, and a portion of the inner layer of the covering wires.

Referring to the drawings, the improved rope is of the flattened strand type, and each strand is provided with a composite core comprising a central wire 1 of the section illustrated, formed with three longitudinal grooves 2 disposed parallel to one another and to the axis of the wire, and spaced at equal distances apart around the periphery. 55 The said grooves 2 which are of substantially semi-circular section, respectively receive and constitute seatings for three circular-sectioned wires 3, the radius of the grooves being the same as that of the wires. These 60 round wires 3 are held by the grooves in definitely spaced relationship and the separated peripheral surfaces of the central wire 1, that is, the radial ribs or parts which are located between each pair of grooves, are 65 slightly curved convexly, as illustrated, the depth of the groove 2 in relation to the diameter of the round wires 3 being such that the centre wire 1 and the outer wires 3 lie 70 substantially flush and together form a core 75 of substantially triangular contour, with the wires 3 situated at the corners or apices of the triangle. This formation is equivalent in shape to the ordinary single or solid triangular core, the round wires 3 taking the place 80 of the solid corners of the said triangular core. As the greatest distance from the axis to the periphery of the central wire is now considerably less than would be the distance 85 of the apices of an equivalent solid triangular core, the said central wire is not so liable to fracture under flexion and compression, such as when the wire is passing around a pulley. Further, there are no sharp edges 90 liable to cause injury to the covering wires 95 4 and 5. Two layers of covering wires are shown, but one, two or more layers of covering wires may be provided, the said covering wires being laid helically around the composite core in the usual manner in order 100 to complete the strand, the composite core being given a definite spiral lay or twist during the process of forming the strand.

The central and outer wires 5 of the composite core may be of any other suitable cross

sectional shape, provided they produce a core of a triangular or substantially triangular form, and instead of the grooves in the central wire of the core being of a semi-circular shape, as stated, they may be of a V-formation, or of any other suitable cross-sectional shape.

Having fully described my invention, what I desire to claim and secure by Letters Patent is:—

- 10 1. A flattened strand for a wire rope comprising a single central wire having three spaced longitudinal grooves, longitudinal wires located in said grooves to produce a composite core of substantially triangular form, and covering wires laid upon the said composite core.
- 15 2. A flattened strand for a wire rope comprising a single central wire having three spaced longitudinal grooves, longitudinal wires laid in said grooves to produce a composite core having substantially the contour of a triangle with the said wires disposed at the corners of the triangle, and covering wires laid upon the said composite core.
- 20 3. A flattened strand for a wire rope comprising a single central wire having three spaced longitudinal grooves, longitudinal wires of circular section laid in said grooves to produce a core having substantially the contour of a triangle with the said wires located at the corners of the triangle, and covering wires laid upon the said composite core.
- 25 4. A flattened strand for a wire rope comprising a single central wire having three spaced longitudinal radial ribs separated by longitudinal grooves, longitudinal wires lying in said grooves substantially flush with the outer surfaces of the ribs to form a composite core having substantially the contour of a triangle, and covering wires laid upon the said composite core.
- 30 5. A flattened strand for a wire rope comprising a single central wire having three spaced longitudinal grooves, longitudinal wires laid in said grooves to produce a composite core of substantially triangular contour said core being twisted spirally, and covering wires laid spirally upon the said composite core.
- 35 6. A wire rope comprising a plurality of flattened strands of triangular contour each consisting of a single central wire having three spaced longitudinal grooves, wires laid in said grooves to produce a composite core of triangular contour, and covering wires laid on the said composite core.

In testimony whereof I have affixed my signature.

ROBERT CHARLES GEORGE JENKIN.
